UNITED STATES PATENT OFFICE.

GEORGE WOODLIFF, JR., AND JULIUS N. MAY, OF CHICAGO, ILLINOIS.

GLOBE RETAINER.

1,412,588.

Specification of Letters Patent. Patented Apr. 11, 1922.

Application filed May 22, 1920. Serial No. 383,563.

To all whom it may concern:

Be it known that we, GEORGE WOODLIFF, Jr., and JULIUS N. MAY, citizens of the United States, and residents of the city of

5 Chicago, county of Cook, and State of Illinois, have invented certain new and useful Improvements in Globe Retainers, of which the following is a specification.

Our invention relates to new and useful 10 improvements in globe retainers, and has for its object the provision of a globe retainer which will be simple in structure, economic of manufacture and highly efficient in use.

15 Another object is the provision of means for mounting a globe upon a pedestal which will allow the globe to yield before the wind to a certain extent and prevent the application of excessive strain upon any particular 20 portion of the globe.

Another object is the provision of a globe retaining member sufficiently resilient to allow oscillation of the globe within a certain degree.

25 Other objects will appear hereinafter.

The invention consists in the combinations and arrangements of parts hereinafter described, and claimed.

30 The invention will be best understood by reference to the accompanying drawings forming a part of this specification, and in which,

Fig. 1, is a broken away side elevational view showing our invention applied to a 35 lamp pedestal,

Fig. 2, is a top plan view of the invention,

Fig. 3, is a bottom plan view of the invention,

Fig. 4, is a fragmentary perspective view 40 of one of the adjoining ends of one of the sections used in the invention.

The invention is designed primarily for use in mounting globes upon street lamps. The street lamp ordinarily used comprises

45 a pedestal 6 upon which is positioned a globe 7 which encloses the light. The pedestal 6 is usually provided with a bead 8 at the upper end thereof. The globe is similarly provided with a flange 9 at its base which is

50 engaged by a retaining member mounted upon the pedestal. In the forms now used, a plurality of screws project through the retaining member and engage the globe above the flange. Inasmuch as these globes 55 are subjected to a great deal of wind, excessive strain is sometimes placed upon the

globe at the point where the screws contact therewith, resulting in a fracture of the globe and some times in a shattering of it. To obviate the fracture and shattering of 60 the globe, we have provided a retaining member which comprises two arcuate semi-circular members 10 and 11 which are hingedly connected together at one end as at 12. These members 10 and 11 are each provided on their under surface with an inwardly projecting flange 13 and on their upper surface with an inwardly projecting flange 14 which is somewhat wider than the flange 13. As shown in Fig. 3, each of the 65 members is provided at its opposite end with lugs 15 and 16 provided with registering openings therethrough for the reception of a bolt 17 and a co-operating nut 18. In mounting the device upon the pedestal, the 70 flange 13 is clasped about the pedestal beneath the bead 8, the flange 14 being clasped about the lower portion of the globe above the flange 9. As shown in Fig. 1, the side walls of the retainer are tapered toward the 75 bottom, thereby making the opening at the top larger than the opening at the base. The purpose of this is to retain the globe 7 in mounted position and prevent its falling down upon the bead 8, the periphery of the 80 flange 9 engaging against the inclined inner walls of the retainer after clasping the members 10 and 11 about the pedestal and globe as described. The members are then secured in locked position by means of the bolt 17 85 projected through the lugs 15 and 16. As shown in Fig. 4, the members 10 and 11 are each provided at one end with an extension 19 which is a continuation of the flange 14 or which may be a tongue connected to the 90 flange, similarly the member is provided with a tongue 20 which may be a continuance of the side wall 11 or a member secured to the side wall. The purpose of the tongues is to give more rigid connection at the points 95 of juncture.

The members 10 and 11 are made of some 100 resilient material and from experience it has been found that if made from sufficiently heavy tin, a very effective device is produced. In constructing the retainer, it is necessary that the flange 14 be sufficiently resilient or pliable to allow the same to be sprung out of its usual plane without the permanent distortion thereof. When the 105 wind strikes the globe and tends to incline it in one direction, the portion of the flange 110

22

14, which represents about one-half of the flange, which is on the windward side, engages securely the flange of the globe and is tilted upwardly with the flange. As soon as the wind subsides sufficiently to allow the globe to resume its normal position, the globe is carried back to its normal position by the resilient flange 14 which has been tilted or raised out of its normal position. It is thus seen that the flange 14 remains in contact with the flange of the globe at all times and permits the globe to oscillate to a certain extent. It is also apparent that when the globe is held in resistance of the wind, the pressure exerted upon the globe is spread over a considerable part of the flange and not centered at one point, which would be the case where screws are used, or contact members which engage a single joint.

20 While we have illustrated and described the preferred form of construction for carrying our invention into effect, this is capable of variation and modification without departing from the spirit of the invention.

25 We, therefore, do not wish to be limited to the precise details of construction set forth, but desire to avail ourselves of such variations and modifications as come within the scope of the appended claims.

30 Having described our invention, what we claim as new and desire to secure by Letters Patent is:—

1. In combination with a pedestal having a bead formed on its upper end portion, of a globe having a flanged rim supported above said pedestal; and clamping members having upper and lower inwardly extending flanged edges engaging the said bead and said flanged rim for supporting said globe above said pedestal to permit free oscillation of said globe thereon, the side walls of said clamping members being tapered toward said bead to prevent said globe from contacting with the upper end portion of said pedestal, substantially as described.

2. A device of the class described comprising a plurality of arcuate members hingedly connected at one end; a laterally extending flange at one side of each of said members for embracing and engaging a lamp pedestal; and a resilient flange at the opposite side for embracing and engaging a globe, said arcuate members being tapered to support the globe therebetween and permit oscillation thereof between said tapered members and the resilient flange, substantially as described.

3. A globe support including hingedly connected clamping members having downwardly and inwardly tapered side walls for engagement with a globe, angular lugs affording means for detachably securing said members together and projections on one of

the adjoining ends of said members adapted to engage the inner surfaces of the opposite adjoining end affording a rigid connection at the point of juncture of said members, substantially as described.

4. In a globe holder, the combination with a globe having a flanged rim, of a pair of co-operating arcuated members having tapered side walls hingedly connected together at one end; angularly shaped lugs on said side walls affording means for detachably securing said members together; an inwardly extending resilient flange formed on said members adapted to embrace said globe; an inwardly extending flange formed on said members arranged to engage the upper end portion of a pedestal for supporting said globe thereabove; and projections formed on one of the adjoining ends of said members adapted to engage the inner surfaces of the opposite corresponding adjoining end affording a rigid connection at the point of juncture of said members, substantially as described.

5. In a globe supporting device, the combination with a pedestal, of a holder clampingly engaging the upper periphery of said pedestal and extending upwardly therefrom, the side walls of said holder being tapered inwardly and downwardly for supporting a globe above said pedestal, substantially as described.

6. In a globe supporting device, the combination with a pedestal, of a holder comprising parts hingedly connected together arranged and adapted to clampingly engage the upper periphery of said pedestal and extending upwardly therefrom, the side walls of said holder being tapered inwardly and downwardly for supporting a globe above said pedestal to permit oscillation of said globe within said holder; and lateral resilient flanges on said holder for preventing separation of said globe from said holder during oscillation of said globe, substantially as described.

7. In a globe supporting device, the combination with a pedestal, of a holder clampingly engaging the upper portion of said pedestal and adapted to support a globe there above to permit oscillation of said globe thereon; and means for preventing separation of said globe from said holder during oscillation thereof, substantially as described.

In testimony whereof we have signed our names to this specification in the presence of two subscribing witnesses.

GEORGE WOODLIFF, JR.
JULIUS N. MAY.
